SCREEN PACKER

Charles W. Thornhill, Houston, Tex.

Application July 19, 1937, Serial No. 154,428

21 Claims. (Cl. 166—12)

This invention relates to a packer and setting mechanism therefor for use in connection with an oil well or the like.

It is the general object of this invention to provide an improved packer and means for expanding the same.

Another object is to provide a packer which may be removed from a well without necessity of breaking up the parts by drilling or otherwise.

Another object is to provide a packer which may be expanded without resting the set shoe on bottom.

Another object of this invention is to provide a packer which may be expanded with a force of any predetermined value.

Another object of this invention is to provide a packer which cannot be moved either upwardly or downwardly within a well once the packer has been set, unless it is first intentionally released.

Another object of this invention is to provide a packer and device for lowering and setting the same, including frangible elements adapted to be severed at the time of setting the packer, but which may be rotated and washed through for the purpose of removing bridges or the like prior to the setting of the packer without danger of breaking the frangible members.

Another object is to provide a device of the type set forth in which the entire structure, including the pipe by which the device is being lowered, may be lifted slightly and dropped for the purpose of driving the device through or past obstructions as it is being lowered without danger of breaking the frangible connections referred to.

Other objects and advantages of this invention will become apparent from the following description, taken in connection with the accompanying drawings, it being clearly understood that said description and drawings are by way of illustration and example only and are not by way of limitation.

In the drawings:

Fig. 1 is a view partly in vertical cross section illustrating the upper portion of a packer and the setting mechanism therefor, construed in accordance with this invention.

Fig. 2 is a view of the lower portion of the structure shown in Fig. 1, Fig. 2 being a continuation of the lower portion of Fig. 1.

Fig. 3 is a view on a reduced scale illustrating the packer shown in Fig. 1 after the same has been expanded.

Fig. 4 is a view similar to Fig. 3, but illustrating the device after the setting string or wash pipe has been removed from the well.

Fig. 5 is an enlarged view illustrating the valve used with the set shoe forming a part of this invention.

Fig. 6 is a view similar to Fig. 1 illustrating a slightly modified form of this invention.

Fig. 7 is an enlarged sectional view illustrating the details of a portion of the latching and expanding mechanism shown in Fig. 6.

In Figs. 1 and 2 the numeral 1 illustrates the well casing hereinabove referred to and the numeral 2 illustrates the drill pipe or tubing upon which the packer and screen and liner are lowered into the well. The lower end of pipe 2 is connected by means of a coupling 3 to a special fitting 4, the upper end of which is similar to the end of a length of the drill pipe or tubing and the lower end of which is formed with an enlarged external diameter 5 having spaced downwardly projecting teeth or clutch members 6 at its lower end. Below the teeth 6 the special fitting, which is again formed with a portion of reduced diameter 7, is internally threaded at 8 to receive a length of wash pipe 9. The lower end of this length of wash pipe 9 is connected by means of a shear pin 10 to a valve member 12, which is of hollow construction and has lateral openings 13 therein adjacent its upper end. This element 12 also has external downwardly facing ratchet teeth 14 for a purpose to be presently described.

The lower portion 7 of the fitting 4 is of such external diameter as to fit snugly within a sleeve 15 and may be joined thereto by means of a shear pin 16, as shown in Fig. 1, and the upper end of this sleeve is provided with spaced upwardly extending tongues or teeth 17 which interfit with the tongues or teeth 6 to provide a rotatable connection between the fitting 4 and the sleeve. The teeth 17 are so formed, however, as to extend radially outwardly beyond the exterior surface of the sleeve, as shown at 18. It will be seen that the lugs or teeth 6 and 17 interfit in such a manner that the shoulder formed by the reduced lower portion 7 of the fitting 4 and the enlarged intermediate portion 5 thereof will rest upon the ends of the teeth 17 and the lower ends of the teeth 6 will rest upon the sleeve 15 between the teeth 17. Thus, it will be possible when lowering the device into a well to permit the weight of the pipe 2 to rest upon the upper end of the sleeve 15 without danger of shearing off the shear pins 16. Furthermore, it is possible to raise the pipe 2, together with the sleeve 15 and the parts carried thereby, and to drop the same in an effort to remove obstructions encountered without any tendency whatever to shear off the pins 16.

The teeth thus make possible the rotation of the sleeve 15 by rotating the pipe 2, and by virtue of the fact that each tooth abuts the end of or a shoulder on the member on which the others are mounted they make possible a raising and dropping of the assembled apparatus for the removal of obstructions. This raising and dropping of the assembled apparatus for this purpose is ordinarily known as "spudding". Below the packer the sleeve is connected by means of a coupling 19 to the screen pipe 20. To the lower end of the screen pipe is threaded a valve seat member 21, having a packing 22 therein. A nut 23 is also threaded into the valve seat 21 and is provided with a ratchet element 24 adapted to engage with the ratchet teeth 14 on the valve element 12. The packing 22 is held in place by means of a washer 25 held against the lower end of the seat member by means of the set shoe 26. The set shoe 26 is hollow and has a central opening 27 and laterally extending blades or fins 28 at its lower end.

While the element 15 is referred to as a sleeve, it will be understood that it may be joined to one or more sections of blank pipe between it and the screen 20, and that the parts 15 which pass through the packer may be of any special form found desirable in practice. It may be pointed out that as shown in the present illustration the element 15 is not an ordinary length of pipe, but is provided with teeth 17 at its upper end and has welded thereto adjacent its lower end a ring 29.

The ring 29 is welded on the exterior of the sleeve as shown at 30, and serves as a support for a ring-like cushion member 31, upon which is carried a plurality of slips 32, having downwardly facing outwardly presented teeth. These slips are in turn connected by means of shear screws 33 to a wedge ring 34 having a downwardly extending part 34' adapted to contact the ring 29 upon upward movement of the slips 32 and slight compression of the cushion member 31. Upon the wedge ring 34 is carried a washer or abutment 35 above which is wound the packer 36. This packer consists, as in the usual case, of a plurality of wrappings of canvas or a similar material held in place by means of wire or the like, or may consist of a circular member of some special compressible composition. The upper end of the packer 36 carries a ring 37 similar to ring 35 and on the upper surface of this ring there rests the plurality of slips 38, having outwardly presented upwardly facing teeth thereon. The slips 38 are connected to a wedge ring 39 by means of a dovetail connection 40.

The wedge ring 39 has an upwardly extending portion 41 of reduced thickness terminating in an open upper end of increased thickness and reduced internal diameter as shown at 42. Against this upper end is adapted to bear a spring 43 held down by means of a washer 44 seated against the coupling 3. The wedge ring 39 is thus constantly urged downwardly by means of the spring 43.

The wedge ring 39 is normally held in its upper position as illustrated in Fig. 1 by means of a pin or pins 45 extending radially through openings in the special fitting 4 and provided on an external portion with inclined upwardly facing parts 46. A sleeve 47 is slidable within the fitting and prevents inward movement of pins 45, and this sleeve is held in position by means of a shear pin 48. A seat 49 is provided within the sleeve 47 for the purpose of receiving a ball valve

50 adapted to be dropped in through the pipe 2. The sleeve 47 is preferably of such size that it fits snugly within the upper portion of the fitting 4, but when moved downwardly from the position shown in Fig. 1 it will enter the enlarged lower portion 5 of the fitting 4 and be intercepted and thereafter supported by the inwardly extending lugs 51 within said fitting. It will then occupy the position shown in Fig. 3 of the drawings.

In operation, the equipment is made up as shown in Figs. 1 and 2 and is lowered into the well to the point where it is desired to set the packer. During this lowering operation fluid may be pumped downwardly through the tubing 2 and the pipe 9, out through the valve 12 and the bottom of the shoe through the opening 27. Thus, any bridges which may be formed may be washed and after the equipment has reached the desired position the entire inside of the well may also be washed. Also, if it be desired to rotate the screen and set shoe at the bottom thereof, or to raise the entire apparatus and drop it a short distance in an effort to remove obstructions, this may be done because of the connection formed between the teeth 6 and 17. When it is desired to set the packer, the ball 50 is dropped into the upper end of the tubing 2 and pumped downwardly until it seats against the seat 49 in the upper end of the sleeve 47. Further pressure from the pumps will then cause this ball and sleeve to move downwardly shearing off the pin 48 until the sleeve comes to rest against the lugs 51 as shown in Fig. 3. This releases the pin or pins 45 for radially inward movement, and by virtue of their inclined outer ends and the corresponding inclined surfaces on the portion 42 of the sleeve 41, the pins 45 will move inwardly and the spring 43 will force the sleeve 41 and the wedge ring 39 downwardly with respect to the fitting 4 and the sleeve 15.

This downward movement of the wedge ring 39 will move the slips 38 outwardly into contact with the inner wall of the casing 1. Thereafter, the tubing 2 is pulled upwardly, moving with it the fitting 4, the wash pipe 9, the sleeve 15, the screen 20, and the set shoe 26. The abutment 29 which is mounted on the sleeve 15 will also be moved upwardly with respect to the anchoring slips 38 which have been set against the casing, and this upward movement will serve to more firmly anchor the slips 38 against the casing. Further upward movement of the tubing 2 will act through the abutment 29, the ring 31, the slips 32, the shear screw 33, the wedge ring 34, and the abutment 35 to expand the packer 36 against the inner wall of the casing. When sufficient stress has been placed upon the packer 36 the shear screw 33 will be sheared off, whereupon the slips 32 will move upwardly along the wedge ring 34 into engagement with the inner wall of the casing, thus locking the wedge ring 34 and the abutment 35 against downward movement with respect to the casing. The parts are so proportioned that after the slips have moved upwardly into locking engagement with the casing as just described and with the cushion member 31 in its natural shape, there will be a relatively small clearance between the abutment 29 and the wedge ring 34. Continued upward pull on the tubing, however, will compress the cushion member 31 until the abutment 29 will come into direct metal to metal contact with the lower end portion 34' of the wedge ring 34. The upward pull on the tubing will then be transmitted directly by an all-metal contact path to the lower

end of the packer, and the cushion member 31 will simply serve to hold the slips 32 always in locking engagement with respect to the wedge ring 34 and the casing 1 without the necessity 5 for transmitting the force for compressing the packer through the slips. The upward pull on the tubing is continued until it becomes sufficiently great to shear off the pins 16 which 10 secure the fitting 4 to the upper end of the sleeve 15, the strength of these pins predetermining the force with which the packer is to be set. As soon as the pins 16 have been sheared, it is of course impossible to further set the packer, and the packer will be held in set position by the slips 15 15 38 and 32.

Upward movement of the tubing 2 with respect to the sleeve 15 and the strainer 20 after the pins 16 have been sheared will serve to move the valve 12 upwardly through the packing 22 until 20 its lower end seats against the packing 22 with the openings 13 above this packing. The ratchet element 24 carried by the nut 23 will thereupon engage the teeth 14 on the valve element and will serve to retain the valve element in seated 25 position. After the valve has been seated, further upward movement of the tubing 2 will cause the shearing of the pins 10, whereupon the connection between the wash pipe and the valve will be severed and the interior of the screen 30 may, if desired, be washed. The tubing 2 or the drill stem, as the case may be, and the wash pipe 9 are now free to be removed from the well if desired so that the tubing which is to serve as 35 a flow line for removing the fluid from the well may be run in.

If it be desired that the same tubing used in setting the packer be also used as the flow line for removing the liquid production from the well, the lugs 51 may be omitted and the parts 40 made of such relative size that the sleeve 41 and ball 50 will pass downwardly within the wash pipe 9 so as to come to rest within the valve element 12. When this is the case, after the packer has 45 been set, the valve 12 seated, and the wash pipe disconnected from the valve, the wash pipe and tubing will be left free and unobstructed so that flow may take place upwardly therethrough.

If after the packer 36 has been set, as above described, it is desired to remove the same for 50 the purpose of reworking the well or for any other purpose, this may be readily done as follows:

The flow tubing within the well is first removed, leaving the parts in the position illustrated in Fig. 4 of the drawings. Thereupon, a 55 fishing device of suitable form is lowered into the well and engaged within the upper portion of the sleeve 41 beneath the bead or enlargement 42. An upward pull on this sleeve by such fishing device will cause the withdrawal of the wedge 60 ring 39 from behind the slips 38, the moving of these slips radially inwardly, and the release of the entire device for upward movement. Because the slips 38 are also connected by a dovetail connection 38' to the ring 37, this movement 65 will also pull the upper end of the packer upwardly. The inner portion of the wedge ring 39 will then engage beneath the outwardly projecting portions 18 of the lugs 17, and will serve to lift the sleeve, screen and other parts attached thereto from the well. The packer 36 being released at its upper end from the hold-down effect of the slips 38, may be torn loose from the casing wall and moved upwardly. Since the teeth 70 on the slips 32 are directed downwardly, they 75 will not interfere with this upward movement,

and the entire device may be removed from the well without breaking the parts and without extensive fishing operations. If it later be desired to use the same structure in the same or another well, it is only necessary to provide a new body 5 of packing material and replace the sheared pins and screws used in connection with the device.

A slightly different embodiment is illustrated in Figs. 6 and 7 of the drawings. In this form the sleeve 41 with its wedge ring 39 has been 10 omitted, and in its place is a ring having a shoulder 52 adapted to receive the spring 43, and having an upstanding portion 53 slidably engaging the exterior of the fitting 4 just above the pin 45. This sleeve is designated by the numeral 15 54 and has leaf springs 55 secured thereto at its lower end by screws 56 or the like. The lower ends of these leaf springs 55 are secured at 57 to a set of slips 58 which are mounted to slide upwardly and downwardly on a wedge ring 59. 20 The wedge ring 59 is itself slidably mounted upon the sleeve 60 which has upstanding teeth or lugs 61 at its upper end which interengage with the lugs 6 on the fitting 4 so as to form a positive 25 rotatable connection. Also the ends of the teeth each abut the opposite member, as in the previously described example, thus making it possible for the device to be spudded. The sleeve 60 is also formed on its exterior surface below the normal position of the wedge ring 59 with a plurality 30 of downwardly directed ratchet teeth 62 adapted to receive the teeth on the spring-pressed ratchet member 63 carried by the wedge ring 59.

In this form, the operations are carried on in 35 a manner similar to that described in connection with the form shown in Figs. 1 and 2. When the ball 50 is dropped into the tubing 2 and comes to rest against the sleeve 47, further pumping will cause the sleeve to move downwardly, shearing the pin 48 in a manner previously described. The 40 pins 45 will then be permitted to move inwardly releasing the sleeve 54 for downward movement under influence of the spring 43. This will move the slips 58 downwardly and outwardly along the wedge ring 59 into contact with the inner wall 45 of the casing 1. An upward pull on the tubing 2 will then serve to first force the wedge ring 59 more firmly behind the slips 58 until the same are set against the casing, and will then serve to compress the packer 36 and move the wedge ring 50 59 downwardly with respect thereto until the teeth of the ratchet member 63 come in contact with the ratchet teeth 62 on the sleeve. The action of the parts at the lower end of the packer will be substantially identical to that previously 55 described, and upon the packer being fully set to the extent predetermined by the strength of the shear pins 16 the same will shear off and release the tubing from the sleeve and packer.

It will be noted from the foregoing that in both 60 forms of the device set forth the screen and set shoe may be rotated or spudded prior to the setting of the packer without in any way endangering the shear pins provided for use in operating the packer. Furthermore, the well may at 65 any time be washed by pumping down through the tubing prior to the time the packer has been set, and the packer itself may be set without any portion of the device being in contact with the bottom of the well.

It is further to be noted that the sleeve, screen and set shoe are at all times positively suspended, and at no time do they have to be rested upon the bottom of the well or any other support. Prior to the setting of the packer these elements 75

are suspended from the tubing, and after the packer has been set and the tubing disconnected they are suspended by the action of the slips 32.

Another feature of this invention lies in the 5 fact that the packer is released for the setting operation by a positive action of the pumps in pumping fluid downwardly through the tubing, and the release is not dependent upon any mechanical manipulation of the tubing from the 10 top of the well.

Thus all of the objects and advantages sought by this invention have been accomplished.

Having described my invention, I claim:

1. In a device for sealing the space between two 15 pipes, an expansible packing between said pipes, means for anchoring one end of said packing against movement with respect to one of said pipes, and means for moving the opposite end of said packing toward the first end to expand the 20 same, said last means including a frangible connection constituting the sole medium for transmitting expanding force to said packing and adapted to be severed to prevent transmission of further expanding force when the expanding 25 force exerted on said packing exceeds a predetermined amount.

2. In a device for sealing the space between two pipes, an expansible packing between said 30 pipes, means for anchoring one end of said packing against movement with respect to one of said pipes, means for moving the opposite end of said packing toward the first to expand the same, said last means including a frangible connection 35 constituting the sole medium for transmitting expanding force to said packing and adapted to be severed to prevent transmission of further expanding force when the expanding force on said packing exceeds a predetermined amount, and means for anchoring said opposite end of the packing against contracting movement after 40 the expansion of the packing has begun.

3. In a device for sealing the space between two pipes, an expansible packing between said 45 pipes, means for anchoring one end of said packing against movement with respect to one of said pipes, and means for moving the opposite end of said packing toward the first end to expand the same, said last means including means for limiting 50 the expanding force exerted on said packing.

5. In a device for sealing the space between two pipes, an expansible packing between said 55 pipes, means for anchoring one end of said packing against movement with respect to one of said pipes, means for moving the opposite end of said packing toward the first to expand the same, said last means including a means for limiting 60 the amount of expanding force transmitted to said packing, and means for anchoring said opposite end of the packing against contracting movement with respect to the same one of said pipes after the expansion of the packer has begun.

6. In a device for sealing the space between two pipes, an expansible packing between said 65 pipes, means for anchoring one end of said packing against movement with respect to one of said pipes, means for moving the opposite end of said packing toward the first to expand the same, slips for anchoring said opposite end of the packing 70 against contracting movement with respect to the same one of said pipes after the expansion of the packing has begun, and resilient means for urging said slips into anchoring position during the time said packing is being expanded.

7. In a device for sealing the space between

two pipes, an expansible packing between said 5 pipes, means for anchoring one end of said packing against movement with respect to one of said pipes, means for moving the opposite end of said packing toward the first to expand the same, slips for anchoring said opposite ends of the packing against contracting movement after the expansion of the packer has begun, and frangible 10 means for normally preventing said slips from being moved to anchoring position, said frangible means until broken constituting a part of said means for moving the opposite end of the packing to expand the same, and adapted to be broken by a force less than that required to fully 15 expand the packing.

7. In combination with a packing for sealing the space about a section of blank pipe within a well, a tubing having a part thereof disposed within said section of blank pipe, said section of blank pipe and said tubing having interfitting 20 parts forming a rotatable clutch connection therebetween, and a frangible means for holding said section of blank pipe and said tubing in position with said interengaging parts engaged with each other to form a positively rotatable connection between said tubing and said section of blank pipe whereby said section of blank pipe may be rotated by rotation of said tubing without disconnection of said parts from each other, and whereby said tubing may be disconnected from said 25 blank pipe after the packing around said blank pipe has been expanded.

8. In combination with a packing for sealing the space about a section of blank pipe in a well, 30 a section of blank pipe within said packing, a tubing having a telescoping connection with said section of blank pipe and having means adapted to limit the amount by which said tubing may telescope with said section of blank pipe, and frangible means for holding said tubing in fully 35 telescoped relation with said section of blank pipe, whereby force may be transmitted through said tubing to said section of blank pipe to move said section of blank pipe into position and said tubing may be removed from said blank pipe by 40 fracturing said frangible connection after said packing has been expanded.

9. In a device for sealing the space between two pipes, an expansible packing between said 45 pipes, means for anchoring one end of said packing against movement with respect to one of said pipes, means for normally holding said anchoring 50 means away from anchoring position, hydraulic means for releasing said anchoring means for movement into anchoring position, and means for moving the opposite end of said packing toward the first to expand the same.

10. In a device for sealing the space between two pipes, an expansible packing between said 55 pipes, means for anchoring one end of said packing against movement with respect to one of said pipes, means movable longitudinally on said pipes to move said anchoring means to anchoring position, resilient means for urging said longitudinally movable means in such direction, means for preventing movement of said longitudinally movable means in such direction, hydraulic means for releasing said preventing means to permit said longitudinally movable means to move and means for moving the opposite end of said packing toward the first to expand the same.

11. In a device for sealing the space between two pipes, an expansible packing between said 60 pipes, slips for anchoring one end of said packing against movement with respect to one of said

- 5 pipes, means movable longitudinally of said pipe to set said slips, resilient means for urging said longitudinally movable means into slip-setting position, a tubing connected to one of said pipes, 5 a pin disposed within an opening in said tubing and adapted when projected outwardly to prevent such longitudinal movement of said longitudinally movable means, a sleeve within said pipe for holding said pin in projected position, 10 means for closing the opening through said sleeve so that upon exertion of hydraulic force upon said last means said sleeve will be forced from behind said pin to release said longitudinally movable means and set said slips, and means for moving the opposite end of said packing toward the first to expand the same.
12. In a device for sealing the space between two pipes, an expansible packing between said pipes, slips for anchoring one end of said packing against movement with respect to one of said pipes, a wedge ring movable behind said slips to expand the same, resilient means urging said wedge ring behind said slips, means for normally preventing movement of said wedge ring to slip-setting position, hydraulic means for releasing said last mentioned means to permit said wedge ring to be moved to slip-setting position, and means for moving the opposite end of said packing toward the first to expand the same.
- 30 13. In a device for sealing the space between a casing and section of blank pipe, an expansible packing about said section of blank pipe, slips for anchoring one end of said packing against movement with respect to said casing, a wedge ring movable behind said slips to expand the same, resilient means for urging said wedge ring toward slip-setting position, means for preventing such movement of said wedge ring, means for releasing said last mentioned means to permit said wedge ring to move to slip-setting position, a laterally projecting part on said blank pipe adjacent the upper end thereof, and inwardly projecting parts on said wedge ring above and below said projection of said blank pipe, whereby said wedge ring may be engaged by a fishing tool to release said slips and will in turn engage the lateral projection of said blank pipe to raise said blank pipe after said slips have been disengaged.
- 50 14. In a device for sealing the space between a casing and section of blank pipe, an expansible packing about said section of blank pipe, slips for anchoring one end of said packing against movement with respect to said casing, a wedge ring movable behind said slips to expand the same, resilient means for urging said wedge ring toward slip-setting position, means for preventing such movement of said wedge ring, means for releasing said last mentioned means to permit said wedge ring to move to slip-setting position, a laterally projecting part on said blank pipe adjacent the upper end thereof, and inwardly projecting parts on said wedge ring above and below said projection of said blank pipe, whereby said wedge ring may be engaged by a fishing tool to release said slips and will in turn engage the lateral projection of said blank pipe to raise said blank pipe after said slips have been disengaged, said slips and said wedge ring being connected to each other by dove-tail connections, and said slips being connected to the upper end of said packing by a dove-tail connection whereby upward movement of said wedge ring will positively contract said slips and lift the upper end of said packing.
15. In combination, a well screen and set shoe therefor, a section of blank pipe at the upper end of said screen, a tubing connected to said blank pipe for lowering said screen, shoe and blank pipe into a well, a normally open valve in said shoe, a frangible connection between said tubing and said blank pipe and between said tubing and said valve, said valve being movable upwardly to closed position on upward movement of said tubing relative to said shoe and said blank pipe, a packing surrounding said blank pipe for forming a seal about said blank pipe, and means operable by simultaneous movement of said tubing, blank pipe, screen and shoe for setting said packing without movement of said tubing relative to said shoe until said packer has been set.
16. In combination, a well screen and set shoe therefor, a section of blank pipe at the upper end of said screen, a tubing connected to said blank pipe for lowering said screen, shoe and blank pipe into a well, a normally open valve in said shoe, a frangible connection between said tubing and said blank pipe and between said tubing and said valve, said valve being movable upwardly to closed position on upward movement of said tubing relative to said shoe and said blank pipe, a packing surrounding said blank pipe for forming a seal about said blank pipe, and means operable by simultaneous movement of said tubing, blank pipe, screen and shoe for setting said packing, and means for preventing relative movement of said blank pipe and tubing until said packing has been set.
- 35 17. In combination, a well screen, a set shoe at the lower end thereof, a blank pipe on the upper end thereof, a normally open valve in said set shoe, a tubing connected to said blank pipe and to said valve and adapted upon upward movement of said tubing with respect to said blank pipe to close said valve, shear pins connecting said tubing to said valve and to said blank pipe with said valve in open position, a packing surrounding said blank pipe to form a seal thereabout, said shear pins connecting said tubing and said blank pipe being adapted to transmit force from said tubing to said blank pipe for compressing said packing, and to give way when said force exceeds a predetermined maximum whereby said valve will remain in open position until said packing has been fully expanded.
- 50 18. In a device for sealing the space between two pipes, a packing between said pipes, gripping means adjacent one end of said packing adapted to be moved into contact with one of said pipes to anchor said end of said packing against movement with respect to said pipe toward said gripping means, means movable along the other pipe toward the packing for urging said gripping means into contact with said one pipe, and means for forcing the opposite end of said packing toward said gripping means to expand the packing.
- 60 19. In a device for sealing the space between two pipes, an expansible packing between said pipes, slips for anchoring one end of said packing against movement with respect to one of said pipes, a wedge ring movable along the other pipe to a position behind said slips to expand the same, means for so moving said wedge ring to expand said slips, and means for moving the opposite end of said packing toward the first end when said slips are expanded.
- 70 20. In a device for sealing the space between two pipes, an expansible packing between said pipes, laterally expansible means for anchoring one end of said packing against movement with

respect to one of said pipes, means movable along the other pipe with respect to said other pipe and said first means to expand the first means, means for so moving said last mentioned means, and means for moving the opposite end of said packing toward the first to expand the same.

21. In combination, a set shoe for a well and a section of blank pipe carried thereby, a tubing connected to said blank pipe for lowering said set shoe and blank pipe into a well, a normally open valve in said set shoe, a frangible connection between said tubing and said blank pipe and

between said tubing and said valve, said valve being movable upwardly to closed position on upward movement of said tubing relative to said shoe and said blank pipe, a packing surrounding said blank pipe for forming a seal thereabout, and means operable by simultaneous movement of said tubing, blank pipe and shoe for setting said packing without movement of said tubing relative to said shoe until said packing has been set.

CHARLES W. THORNHILL.
